UNITED STATES PATENT OFFICE.

EDWARD POSSON, OF CHICAGO, ILLINOIS.

RAILWAY TANK-CAR.

1,095,350.

Specification of Letters Patent.

Patented May 5, 1914.

Application filed February 16, 1912. Serial No. 678,103.

To all whom it may concern:

Be it known that I, EDWARD POSSON, a citizen of the United States, residing at Chicago, in the county of Cook and State of Illinois, have invented certain new and useful Improvements in Railway Tank-Cars, of which the following is a specification.

The principal object of my invention is to provide a new and improved construction to 10 be used in mounting a tank upon the under-frame in a railway tank car.

Another object of my invention is to provide means for attaching a tank to the underframe of a railway tank car, that shall 15 provide for unequal expansion due to heating of the tank.

Another object of my invention is to provide a construction by which a tank may be detachably mounted on the underframe of a 20 railway tank car.

These and various other objects will be understood from the following specification and claims, taken in connection with the accompanying drawings, in which—

25 Figure 1 is a side elevation of a tank car comprising my improvement, certain parts being broken away to show the structure more clearly. Fig. 2 is a side elevation on an enlarged scale of the structure that constitutes my improvement. Fig. 3 is a cross section showing the improved features in greater detail. Fig. 4 is a similar cross section on a smaller scale, showing the parts more extensively.

35 The underframe of the car comprises the center sill consisting of parallel plates 15 lying in vertical planes and covered by a top plate 16. The angle irons 17 join the side plates of the center sill to the top plate. 40 The flat horizontal plates 18 are riveted to the upper corners of the center sill, so that their edges project outwardly therefrom, as shown in the drawings.

The underframe of the car carries six 45 longitudinally extending wooden members 25, distributed as shown in Fig. 4, which form a cradle on which the tank rests.

50 A plate of sheet metal, designated generally as 20, is bent in channel or trough-like form, the cross section being shown in the drawings. The intermediate web 21 is slotted for a limited distance from the ends, the slots being designated 27 in the drawings. The upper flange 22 is riveted to the tank

19 and the lower flange 23 overlies the outwardly projecting part of the previously described plate 18. The plate 18 and the flange 23 are provided with registering holes in which are the bolts 24 normally binding the parts together. The filler plate or shim 26 goes between the flange 23 and the plate 18 and may be of any proper thickness.

It will be seen that the weight of the tank is supported entirely by the wooden cradle members 25 and the function of the member 20 and its associated elements is to hold the tank against longitudinal displacement in the cradle.

It not infrequently happens that in cold weather or at other times it becomes desirable to heat the oil in a tank car. This may be done by immersing steam coils in the oil and passing steam through them. Of course, the heating of the oil also heats the walls of the tank and causes expansion of the latter. 70 For this reason the slots 27 are provided so that the flange 22 can expand with the tank without causing undue stress and strain on the intermediate web 21. The tank, of course, should rest securely on the wooden 80 timbers 25 and the shims 26 may be introduced between the plates 18 and the flanges 23 in order to secure a proper adjustment.

When it is desired to remove the tank from the car underframe the bolts 24 can 85 be removed and then the channels 20 will go with the tank 19 while the plates 18 will stay with the underframe. If rivets are used in place of the bolts 24 they will have to be cut in case the tank is to be removed. 90 This would be a slight disadvantage which would be compensated in a measure by the certainty that the rivets would not become loose as bolts might do.

It will be seen that I have provided a 95 simple and secure construction for connecting the tank to the underframe, and that furthermore I have arranged this construction so that when it is desired to remove the tank from the underframe, this can be readily accomplished.

I claim:

1. In a device of the class described, a car underframe, a tank supported thereby, a plate permanently fastened to the said underframe, a member with a projecting flange permanently fastened to the tank, said plate on the underframe and member

on the tank having holes, and securing means in said holes binding the parts together.

2. In a device of the class described, a car underframe, a tank supported thereby, a member with two flanges, one flange being riveted to said tank and the other flange spaced therefrom, and securing means engaging said spaced flange and fastening the

same to the said underframe, said member 10 being slotted in from its ends between its flanges.

In testimony whereof, I have subscribed my name.

EDWARD POSSON.
